HEAT EXCHANGER

Wilbur A. Shaw, Forest Hills, N. Y., assignor to
 American Locomotive Company, New York,
 N. Y., a corporation of New York

Application March 19, 1942, Serial No. 435,315

2 Claims. (Cl. 257—240)

This invention relates to heat exchangers, and more particularly to jet-type exchangers.

The present invention is directed to increasing the heat transfer rate of an exchanger so that a smaller exchanger can be employed to do the same amount of work ordinarily done by a larger exchanger. For example, the exchanger shown in the drawing forming a part of this application is a jet-type lube oil cooler adapted for employment with a Diesel engine. It is desirable to keep the exchanger as small as possible so that it can be conveniently mounted on the Diesel engine, forming an auxiliary thereof. It functions to cool the lubricating oil after a lubricating cycle. The present invention has application, of course, to jet-type exchangers designed for other purposes. However, for simplicity, the following description will be restricted to the lube oil cooler as shown.

It is a fact well known in the heat exchange art that laminar flow of a liquid over the outside of the tubes of a tube bank produces a stagnant film of liquid adhering to the outer surfaces of the tubes. This film is of a thickness proportional to the velocity of flow of the liquid; between the tubes there is a flow of essentially parabolic velocity distribution. The aforementioned film resists the transfer of the heat between fluid inside of the tubes and the liquid outside, with a resultant decrease in transfer rate. If the tubes are fin tubes, and thus necessarily spaced farther apart than plain tubes, the free cross-sectional area for flow between the tubes is greater, resulting in lower velocities and lower transfer rate.

An object of the present invention is to provide a heat exchanger having means for minimizing film formation, thereby increasing transfer rates.

A further object is to provide in an exchanger of the aforesaid characteristics means producing small net free flow areas at intervals in the shell thereof, thereby increasing velocity of, and creating turbulence and remixing in, the flow through the shell.

A further object is to provide an exchanger which can be made in a smaller size than conventional design to handle the same heat duty.

Other and further objects of this invention will appear from the following description, the accompanying drawing and the appended claims.

Referring to the drawing forming a part of this application, Figure 1 is, at the left, a plan view of an exchanger embodying the present invention, and at the right the cover is removed,

5 a portion of the tube sheet is broken away and the baffles and tube exposed are shown in section on a line taken through the upper perforations; Fig. 2 is, at the left, a side elevation of the exchanger, the fins on the tubes not being indicated, and at the right a section on the line II—II of Fig. 1, parts being shown in full, some fins being shown and the remainder of the finned area being indicated by dot and dash lines; 10 Fig. 3 is a section on the line III—III of Fig. 1, fins being shown and indicated as in Fig. 2; and Fig. 4 is a fragmental plan view of a modified heat exchanger, the tube sheet and cover being removed and the baffles and tubes being shown 15 in section on a line taken through the upper perforations.

The lube oil cooler is indicated generally by the reference numeral 1. It includes a welded built-up shell 2, box-shaped and open at the upper end, a bolting flange 3 being welded around the upper edge. The shell has a front wall 4 provided with an inlet 5 formed by a nozzle welded in a port in wall 4, and a rear wall 6 provided with an outlet 7 formed by a nozzle welded in a port in wall 6. The shell further includes side walls 8.

30 A series of parallel spaced perforated shell-partitioning baffles 9 are disposed in the shell, extending between and welded to the side walls 8, and being at their bottoms welded to the bottom wall 10 of the shell. The tops of the baffles are flush with the top of the bolting flange 3. An inverted V-cut 11 is formed in the bottom of each baffle to allow complete drainage 25 through drain opening 12 when desired. Opening 12 is ordinarily closed by plug 13. A shell vent 14, closed by a plug 15, is provided in the bolting flange 3.

The baffles 9 are equally spaced from each other. The front baffle is spaced from the wall 4 and the rear baffle from the wall 6. Each baffle has four vertical rows of vertically extending slot-shaped perforations 16. These perforations are so shaped and proportioned as to provide the desired reduced free area for flow through the shell from the inlet to the outlet, and are sufficiently restricted to jet the liquid flowing through them, for a purpose presently to appear.

45 A tube sheet 17 is supported on the bolting flange, having orifices in line with orifices in the flange. A gasket 18 is disposed between the tube sheet and flange. This gasket may be ring-shaped, covering only the flange, or it may 50 cover the entire bottom face of the tube sheet,

having orifices in line with tube sheet orifices, and being engaged by the baffles to seat their upper edges. The tube sheet has a row of orifices 19 adjacent one wall 8, there being one orifice between each adjacent pair of baffles, and a similar row of orifices 20 adjacent the other wall 8.

A U-bend tube 21, formed of a row of straight legs connected progressively by U-bends, is disposed between each adjacent pair of baffles with the planes of the baffles and rows of legs parallel. Each tube 21 has an inlet leg 22 expanded at its free end in the adjacent orifice 20 and depending into the shell. Leg 22 is connected by a U-bend 23 to an upwardly extending leg 24, the U-bend being in the bottom of the shell. Leg 24 is connected by a U-bend 25 to another downwardly extending leg 26, U-bend 25 being disposed in the shell adjacent tube sheet 17. Leg 26 is connected by a U-bend 27, at its lower end, to an upwardly extending outlet leg 28 which is expanded at its upper free end in the adjacent orifice 19. U-bend 27 is disposed similar to U-bend 23. Each leg has secured to its outer face radial horizontal fins 29. Other types of fins may be employed, however, and it has been found that a continuous helical fin is well suited for use in the cooler 1. In Figs. 2 and 3 the fins are only shown at the top and bottom of the straight portions of the legs. However the entire straight portions of all legs in the cooler are finned, this being indicated in Figs. 2 and 3 by vertical dot-dash lines *a*.

The legs of the U-bend tubes are disposed with their axes in line with the adjacent rows of perforations, as is shown in Fig. 3. That is to say, all the legs 22 and the adjacent perforations of the baffles are in the same vertical plane. This is also true of the other legs.

A cover 30 is supported on top of the tube sheet by means of a bolting flange 31 having orifices in line with the adjacent tube sheet and bolting flange 3 orifices. A gasket 32 is disposed between flange 31 and the tube sheet. Bolts 33 secure the cover, tube sheet and shell together, the cover and the tube sheet together forming a header, the tube sheet forming the bottom wall of the header and closing the open upper end of the shell.

The header is divided into an inlet compartment 34 and an outlet compartment 35 by a partition 36 which is supported by the cover 30 and sealed against the tube sheet by a gasket 37 which may be made as part of gasket 32 if desired. Cover 30 is shown as a casting, although it may be built up if desired. It has an inlet nozzle 38 opening into compartment 34 and an outlet nozzle 39 opening into compartment 35. All the legs 22 open into compartment 34 and all the legs 28 open into compartment 35.

The operation of the cooler 1 is as follows: Hot lubricating oil from the Diesel engine enters shell 2 through inlet 5, entering the space between wall 4 and the first baffle 9. As the oil is under pressure, say for example forty pounds, it is forced through the perforations 16. As the perforations are axially in line with the legs of the first U-bend tube 21, the oil is jetted directly on the legs. The perforations are so proportioned and shaped that the oil flows therethrough and impinges against the legs under considerable velocity, which velocity and impingement minimizes film stagnation on the legs, wiping off any that may have formed, causes

turbulent flow between adjacent baffles, and effects an increased heat transfer rate between the oil and the fluid in the tubes, which in the instant case will be cooling water. The turbulence furthermore causes a mixing of the oil providing uniform cooling.

The cooling water enters the header through inlet nozzle 38. It flows from compartment 34 simultaneously into all legs 22, legs 22 thus being arranged for parallel flow. The legs of any one tube are arranged for series flow. The cooling water thus enters each tube at the same temperature. However, the temperature in the outlet legs 28 varies successively from the front to the rear of the shell, being hottest at the front. Legs 28 expel the heated water into outlet compartment 35.

The oil, as aforesaid, is impinged directly on the legs of one tube, so that hot oil of uniform temperature passing through the first baffle is treated by cooling water in a single tube, the water naturally being cooler in the inlet leg than in the outlet leg, as aforesaid.

The first baffle effects only a slight drop in pressure in the oil, so that the oil passes through the perforations of the second baffle and is jetted against the second U-bend tube. This operation is repeated until the oil passes out of outlet 7 in a cooled state. Thus the oil has series flow through the baffles and is treated in series by the tubes. Each time the oil passes through a baffle it is cooler. Each of the U-bend tubes is receiving water at uniform low temperature, as aforesaid, so that the oil is always treated by cold water between adjacent baffles, there being no U-bend tube between baffles which receives water heated by a previous step in the heat transfer.

The oil flows through the shell longitudinally thereof, the length of the shell being determined by the direction of flow of shell liquid, and the water flows through the tubes transversely of the shell. There is no longitudinal water flow. This enables the legs of a U-bend tube to be disposed entirely between two adjacent baffles, as shown, the U-bend tube thus being removable from the shell without disturbance of the baffles. Thus, when it is desired to clean the fins or shell, it is only necessary to remove bolts 33 and lift the tube sheet and U-bend tubes as a unit from the shell with its baffles. This is an important advantage of the present heat exchanger.

The modified heat exchanger of Fig. 4 is like the cooler 1 except that the baffles 40 have louvre-shaped perforations 41. These are formed by making, for each perforation, a single straight cut in the baffle and forcing the metal at one side of the cut out into the louvre shape. The flow through a row of louvres will be inclined to the baffle. Therefore to induce the desired impingement the row is disposed at one side of its correlated tube leg and parallel to the axis thereof. The disposition of the rows of louvre-shaped perforations is clearly shown in Fig. 4, the inlet 42 in this exchanger being at the right, the two inner rows of perforations being side by side and oppositely directed. The operation of the cooler of Fig. 4 is similar to the cooler 1.

The heat exchanger of the present invention, as aforesaid, may be employed otherwise than as a cooler and with other fluids than those described. Furthermore, the perforated baffles may be made in other ways. For instance, the per-

forations 16 might be joined to form one long continuous slit.

The baffles perform two main functions. First, they reduce the net free flow area of the exchanger in that the shell liquid must flow through a smaller area to pass from tube to tube than it would were no baffles employed, the net free flow area in such case being that not occupied by the U-bent tube. Second, the perforations cause a jet flow against the tubes. Both the decrease in net free flow area, which increases velocity, and the jetting, effect increases in heat transfer rate.

The baffles, as aforescribed, are arranged across the shell liquid flow from the shell inlet to the shell outlet for series flow through the baffles. There is a baffle in front of the first U-bent tube and a baffle after the last U-bent tube. However, if desired, there may be a U-bend tube in the space between wall 4 and the adjacent baffle and in the space between wall 6 and the adjacent baffle, these spaces in such case being made of a suitable width for this.

While there have been hereinbefore described approved embodiments of this invention, it will be understood that many and various changes and modifications in form, arrangement of parts and details of construction may be made thereto without departing from the spirit of the invention, and that all such changes and modifications as fall within the scope of the appended claims are contemplated as a part of this invention.

The invention claimed and desired to be secured by Letters Patent is:

1. A heat exchanger comprising a shell having an open end and an inlet and an outlet port; a header secured to said shell, closing said open end, and having a tube sheet and ported inlet and outlet compartments; parallel spaced perforated

- shell-partitioning baffles disposed in said shell for series flow therethrough of fluid under pressure; and U-bend fin tubes in said shell, each having its free ends secured in said tube sheet, opening respectively into said inlet and said outlet compartments, and being formed of a row of straight legs connected progressively by U-bends, each tube being disposed adjacent a baffle at the outlet shell port side thereof and having its plane parallel thereto, the perforations of said adjacent baffle being arranged in rows, a row being parallel and adjacent to each leg of said adjacent tube, the perforations thereof being shaped and proportioned to jet shell fluid against said adjacent leg, said perforations providing series flow through said baffles.
2. A heat exchanger comprising a shell having an open end and an inlet and an outlet port; a header secured to said shell, closing said open end, and having a tube sheet and ported inlet and outlet compartments; parallel spaced louvred shell-partitioning baffles disposed in said shell for series flow therethrough of fluid under pressure; and U-bend fin tubes in said shell, each having its free ends secured in said tube sheet, opening respectively into said inlet and said outlet compartments, and being formed of a row of straight legs connected progressively by U-bends, each tube being disposed adjacent a baffle at the outlet shell port side thereof and having its plane parallel thereto, the louvres of said adjacent baffle being arranged in rows, a row being parallel to and offset to one side of each leg of said adjacent tube with the louvre openings extending lengthwise axially of and directed toward said leg, said louvres being shaped and proportioned to jet shell fluid against said adjacent leg, said louvres providing series flow through said baffles.

WILBUR A. SHAW.
